(57) **CLAIM**

The ornamental design for a wire frame rack for dishwasher, as shown and described.

DESCRIPTION

FIG. 1 is a perspective view of a wire frame rack for dishwasher according to an embodiment of my new ornamental design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines represent environmental structure or unclaimed portions of the rack and do not form a portion of the claimed design.

The dotted lines represent the border between claimed and unclaimed subject matter and do not form a part of the claimed design.

1 Claim, 5 Drawing Sheets
